[57] CLAIM

The ornamental design for a fume capture hood, as
shown and described.

DESCRIPTION

FIG. 1 is a front elevational view of the fume capture
hood showing our new design.

FIG. 2 is a left side elevational view thereof, the right
side being a mirror image of the left side shown.

FIG. 3 is a top plan view thereof.

FIG. 4 is a bottom plan view thereof.

FIG. 5 is a rear elevational view thereof.

FIG. 3FIG. 4FIG. 5
